INDUCTIVELY ACTUATED LOUD SPEAKER

Filed Feb. 12, 1926

FIG. 2

FIG. 3

John DePew INVENTOR

BY
L. George D. Vande
ATTORNEY

UNITED STATES PATENT OFFICE

JOHN DEPEW, OF NEW YORK, N. Y., ASSIGNOR TO IGNATZ LAUTER, OF NEW YORK, N. Y.

INDUCTIVELY-ACTUATED LOUD-SPEAKER

Application filed February 12, 1926. Serial No. 87,975.

My invention relates to loud speakers of the general type suitable for use with radio broadcasting receivers, electrically operated sound amplifiers, receivers of various types used in wire and wireless telephony, and in fact in practically all relations in which loud sounds are to be produced initially, or ordinary sounds are to be amplified, by means of small initial variations in the electromotive force or amperage of electric currents.

In my improved loud speaker I take advantage of the attraction and repulsion developed between two windings when energized by alternating or oscillating currents. I make these windings of the pancake type, one of the windings being movable wholly or in part relatively to the other and preferably carrying a thin imperforate member of sheet material adapted to serve as an acoustical diaphragm and to produce sounds when actuated.

As an alternative I may make the two windings stationary and place a diaphragm, made very light and of insulating material, between them. This diaphragm would be made to vibrate by the attraction and repulsion of the windings when said windings are energized, and thus to produce sounds.

In addition I take advantage of the fact that the efficiency of the winding for the purposes here contemplated may be greatly improved by so energizing the windings that the action of one is retarded slightly in relation to the other, the retardation being caused by an impedance properly arranged in the circuit or circuits in which the windings are included and whereby they are energized.

Other objects and aims of the invention, more or less specific than those referred to above, will be in part obvious and in part pointed out in the course of the following description of the elements, combinations, arrangements of parts and applications of principles, constituting the invention, and the scope of protection contemplated will be indicated in the appended claims.

In the accompanying drawings which are to be taken as a part of this specification, and in which I have shown merely a pre-

ferred form of embodiment of the invention:

Figure 1 is a perspective view of one form of my improved loud speaker, the electric circuits for controlling the same being shown diagrammatically.

Figure 2 is a fragmentary vertical sectional view through the loud speaker.

Figure 3 is a fragmentary vertical sectional view through another form of my loud speaker.

I will first describe the form shown in Figures 1 and 2.

A supporting base appears at 4, and is provided with a slideway 5, as shown more particularly in Figure 2. A spider ring 6, made of insulating material, is fitted loosely into the slideway, resting upon the bottom thereof as indicated in Figure 2, and is thus free to slide back and forth, with a vibratory motion, within limits permitted by the width of the slideway. The spider ring is provided with an annular groove 7. For illustrative purposes this ring is here shown as rather massive, but it can be made as thin and light as conditions may require.

A pancake winding is shown at 8. This is made of an insulated wire wound spirally and preferably having as a whole the proximate form of a cone. A thin and light sheet 9 of insulating material 9 is secured to the winding by means of shellac or other appropriate adhesive and is thus carried bodily by the winding and movable therewith. The purpose of the sheet 9 is two-fold, first, to give strength and rigidity to the winding, and second, to render the winding imperforate, both so that it may properly and efficiently act as an acoustical diaphragm, and here it is noted that if desired the sheet 9 may be omitted and a coating of shellac or the like applied to the winding be relied upon to give the required strength and rigidity.

In either instance the winding 8 is secured to the ring 6 for support.

A second pancake winding as 11, is rigidly secured to the base by means of the attaching part 10 of the base. This last mentioned pancake winding is also made of insulated

wire wound in the same form as the winding 8 so as to stand parallel therewith the various convolutions being spaced apart, and secured or braced by means of sectors 13 of shellac or other appropriate binding and insulating material applied practically as a cement and then allowed to dry and harden.

By this means the winding 11 is made to permit the easy passage of air and sound waves therethrough from the diaphragm winding 8.

A conducting wire 12 may be used to connect together the two pancake windings so that they are in series or otherwise with each other relatively to the circuit whereby they are energized.

The diaphragm winding 8 is provided with a binding post 15, and the stationary winding 11 is similarly provided with a binding post 16.

The direction in which the wires of the respective windings are wound is preferably such that, reckoning from the binding posts 15 and 16, the direction is the same, or in other words that from the binding posts, the wires run parallel with each other. However, if desired, this arrangement can be reversed, so that from a given point the direction of one of the windings relatively to its binding post is clockwise and the direction of the other is counter-clockwise.

An audion tube appears at 17, an aerial at 18, a B battery at 19, an A battery at 20, a filament at 21, and at 22 is a circuit including the A battery and the filament 21, and thus designated as the filament circuit.

The aerial 18 is connected by an aerial wire 23 with the audion grid 24.

From the B battery 19 a wire 25 leads to an impedance coil 26. While this impedance winding is here shown conventionally and thus without an iron core, it may if desired be provided with an iron core. However, any other form of impedance may be substituted for the impedance coil 26. Connected with the impedance coil 26 is a wire 27, to which is joined a wire 28, leading to a binding post 15, and a wire 29, leading to the plate 30 of the audion tube 17.

Connected with B battery 19 is a wire 31. Connected with this wire is a wire 32, leading to the binding post 16, and another wire 33. Connected with the wire 33 is a wire 34, leading to the heating circuit 22, and a ground wire 35, communicating with the earth at 36 through the medium of a grounding switch 37 here shown as open.

A purpose of the impedance coil 26 is to retard the action of the diaphragm winding 8 relatively to that of the stationary winding 11, and thus by slightly displacing the current phases of the two pancake windings to increase the attraction and repulsion of the two pancake windings relatively to each other.

By virtue of the slight phase displacement brought about by the action of the impedance coil 26 as just described, and the consequent lagging in the action of the diaphragm winding 8, differences of potential, necessarily developed between the diaphragm winding 8 and the stationary winding 11, are rendered dependent upon, and controllable by, the action of the audion 17.

The effect of the attraction and repulsion between the windings is to cause the winding 8, to move as a unit bodily back and forth relatively to the winding 11, and thus to act as a diaphragm and throw off sounds. These sounds are made up of sound waves having the characteristics of the sound waves which, at a distant station, as for instance a broadcasting station, control the production of electro-magnetic waves which travel through space and energize the audion 17 by means of the aerial 18, aerial wire 23 and audion grid 24.

The circuits, except for the action of the impedance coil 26 as above described, are well known and need no further description.

In the form of my device shown in Figure 3 the supporting base appears at 38, and carries a stationary ring 39, provided with a groove 40. Located within this groove and held rigidly in position by cement or the like 41 and 42 are two pancake windings 43 and 45 preferably of substantially conical form. Both of these windings are constructed with binder sectors 44 for the same purpose as described for the stationary winding 11.

The two pancake windings 43 and 45 are spaced slightly apart and loosely located within this space is a diaphragm 46, made very thin and light, and of insulating material.

The operation of the form shown in Figure 3 differs from that of the other form in that the two pancake windings 43 and 45 are each always stationary, and the diaphragm 46 is free to vibrate between them, being alternately attracted and repelled by each of them in succession.

The circuits employed would be the same as already described.

Owing to the retardation or lag caused by the impedance coil 26, substantially as above described, the pancake winding 43 is energized an infinitesimal period of time before or after the pancake winding 45, each time there is a variation in the electromotive force of the battery current. This retardation or lag causes the pancake windings to act at slightly different moments upon the diaphragm 46, the result being that the movements of this diaphragm, first in one direction and then in the opposite direction, are well defined.

This vibratory motion causes this diaphragm to act substantially like any other diaphragm in producing and throwing off sound waves.

I point out, in addition, that in my device the diaphragm, though made of considerable area, is easily energized throughout practically its entire area, and that this fact makes for greatly improved efficiency.

5 While I show my invention as used in connection with an aerial and thus as under control of electromagnetic waves, it will be understood that I may substitute any known 10 equivalent for the aerial, and thus may control my device by means of a telephone line or by any other agency capable of energizing an audion or equivalent instrument in the conventional manner. Thus the particular circuit 15 shown and described is not essential.

While I have shown and described a particular means for holding the plates and the diaphragm in their respective operative positions nevertheless any other appropriate 20 means may obviously be employed to this end.

It will also be understood that I claim for 25 my loud speaker all of the uses to which a loud speaker can be applied, and that as many changes could be made in this construction without departing from the scope of the invention as defined in the following claims, it is intended that all matter contained in the 30 above description or shown in the accompanying drawings shall be interpreted as illustrative only and not in a limiting sense.

Having thus described my invention, what I claim as new and desire to secure by Letters Patent is:

1. A device of the class described comprising 35 a pair of pancake windings spaced apart and disposed in parallel relation to each other, means for charging said pancake windings in opposite sign and to varying degrees of electromotive force, means for retarding the action of one of said windings relative to the other, and a diaphragm made of insulating material and disposed adjacent both of said pancake windings, and movable by the 40 attraction and repulsion thereof.

45 2. A device of the class described, comprising a diaphragm of insulating material and a pair of pancake windings, said diaphragm and said pancake windings being nested together and each having the proximate form 50 of a cone, said diaphragm being suitably positioned to be acted upon by both of said pancake windings, means for subjecting both of said pancake windings to variations in electromotive force, and means for retarding the 55 action, upon said diaphragm, of one of said pancake windings relatively to the other one.

3. A device of the class described comprising 60 a pancake winding having the general proximate form of a cone, a diaphragm loose relatively to said pancake winding and having also the proximate form of a cone, said diaphragm being made of insulating material and movable bodily in relation to said pancake winding, and means for subjecting 65 said pancake winding to varying degrees of

electromotive force for the purpose of causing it to attract and repel said diaphragm.

4. A device of the character described comprising a pair of pancake windings spaced apart and disposed in parallel relation to each other, means for energizing said pancake windings by charging them in opposite sign and to varying degrees of electromotive force, means for retarding the action of one of said windings relatively to the other, and a diaphragm located between said pancake windings and movable relatively thereto, said diaphragm being made of insulating material.

5. A device of the character described comprising a pair of pancake windings arranged 80 in substantially parallel relation close together, means for variably energizing said windings, and a diaphragm of insulating material disposed adjacent both of said windings, and movable relatively thereto.

In testimony whereof I affix my signature.

JOHN DEPEW.
